Primary Examiner — Sandra Morris(74) Attorney, Agent, or Firm — Gardere Wynne Sewell LLP(57) CLAIM

The ornamental design for a set of gaming tables, as shown and described.

DESCRIPTION

FIG. 1 is a perspective view of a set of gaming tables in accordance with the invention; and,

FIG. 2 is a plan view of the set of gaming tables shown in FIG. 1.

The bottom view is flat and unornamented.

The broken line showing is for illustrative purposes only, and forms no part of the claimed design.
